Primary Examiner — Sandra L Morris

(57) **CLAIM**

We claim the ornamental design for a football bottle, as shown and described.

DESCRIPTION

FIG. 1 is a front elevational view of the football bottle showing our new design;

FIG. 2 is a perspective view thereof;

FIG. 3 is a perspective view thereof, with the top removed from the bottom;

FIG. 4 is a right elevational view thereof; and,

FIG. 5 is a perspective view thereof, with the top removed for ease of illustration.
